S. Darling,

Car Ventilator.

No. 100,870.

Patented Mar. 15. 1870.

INVENTOR.

Samuel Darling

United States Patent Office.

SAMUEL DARLING, OF PROVIDENCE, RHODE ISLAND.

Letters Patent No. 100,870, dated March 15, 1870.

RAILROAD-CAR VENTILATOR.

The Schedule referred to in these Letters Patent and making part of the same.

To all whom it may concern:

Be it known that I, SAMUEL DARLING, of the city and county of Providence, in the State of Rhode Island, have invented certain new and useful Improvements in "Ventilating Railroad Cars;" and I do hereby declare that the following specification, taken in connection with the drawings, making a part of the same, is a full, clear, and exact description thereof.

The drawing represents a car with my improvements attached.

The drawing is intended to show one part of the window closed, and the other part swung around so as to rest against, or nearly so, the part closed.

The object of my invention is to furnish a car with a constant supply and circulation of fresh air, and at the same time exclude the cinders and dust, and consists in the device for admitting the air, and the peculiar construction of the windows for the escape of the same, as hereinafter described.

It is well understood that the necessity of traveling by railroad is steadily increasing, and that a large proportion of our population is daily conveyed by this medium to their several places of destination.

It is therefore incumbent upon railroad companies to provide their passengers with all reasonable comforts, and especially to furnish them with a constant and abundant supply of fresh air.

I construct the windows, as shown in the drawings, in two parts, A and A', which are hung to a perpendicular post, B, and swing like an ordinary door, and when closed, stand at an angle with the side of the car of about forty degrees.

The doors, being made to swing in either direction, may be pushed out parallel with the sides of the car or swung in the opposite direction, to any desired angle.

Thus while the car is in motion, the part of the window nearest the forward end should be kept closed, while the other may be opened as suits the pleasure and convenience of the passenger, either by pushing it out parallel with the sides of the car or swinging it in, as shown by the part A in the drawing.

The part of the window that remains closed being at an angle with the side of the car throws off the cinders and dust in a manner well understood.

The same principle may, however, be employed in windows differently constructed. For instance, the lower part may be made with two small doors, at an

angle with the side of the car, while the upper part will be the same as an ordinary window. The lower part may either be attached to and slide with the upper, or be independent thereof and remain stationary.

In introducing fresh air, I propose to reduce its velocity, before it reaches the interior of the car, to such a degree that it will not sustain and carry the cinders and dust. For this purpose I construct in the top of the car a hollow compartment, C, closed at one end, and partially opened at the other, into which the air is conveyed by the tube D.

The tube D is crooked, or provided with a knee, so that the end that is within the compartment shall be so directed that it will deliver the air against the closed end of the same. Thus an equal distribution of the air will be obtained in the compartment C, and its velocity reduced in proportion as the size of the compartment exceeds the diameter of the tube D, and to such an extent that the cinders and dust will fall, and remain in the compartment C, while the air passes through the aperture E into the car.

The tube D is open at all times for the admission of the air, but the window is subject to the pleasure of the passenger. It will therefore be readily seen that the circulation will be increased or diminished as the window is opened or closed. Thus each passenger has access to the means of ventilation, and can easily regulate his supply of fresh air, as his comfort may require.

What I claim as my invention, and desire to secure by Letters Patent, is—

1. A car-window, composed of two sashes or doors A and A', arranged at an angle with the side of the car, and swinging horizontally, the whole constructed and operating substantially as described.

2. The device for admitting the air, consisting of the tube D, in combination with the compartment C, the whole constructed and operating substantially as described.

3. A window, constructed as described, in combination with the device for admitting the air, and operating in connection with each other, in the manner and for the purposes substantially as described.

SAMUEL DARLING.
